(57) **CLAIM**

The ornamental design for a door component extrusion, as shown and described.

DESCRIPTION

FIG. 1 is a front isometric view of a door component extrusion showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

In FIGS. 1–5, the door component extrusion is shown with a symbolic break in its length signifying length thereof. The appearance of any portion of the door component extrusion between the break lines forms no part of the claimed design. In FIGS. 1–5, the door extrusion component is shown with a symbolic break in its length. The broken lines at the symbolic break form no part of the claimed design. The appearance of any portion of the door extrusion component between the break lines shown form no part of the claimed design.

1 Claim, 7 Drawing Sheets
